ATTORNEYS

UNITED STATES PATENT OFFICE.

LEWIS ELY STEPHENS, OF FELLOWS, CALIFORNIA.

CASING WASHER.

Application filed February 21, 1924. Serial No. 694,310.

To all whom it may concern:

Be it known that I, LEWIS ELY STEPHENS, a citizen of the United States, and a resident of Fellows, in the county of Kern and State of California, have invented certain new and useful Improvements in Casing Washers, of which the following is a specification.

This invention relates to a casing washer, and is especially designed for use with the perforated casings of wells although of course adapted for use with other similar casings.

The object of the invention is to provide a casing washer of this character which effectively applies the cleaning fluid so as to obtain a highly efficient cleansing action and which is economical in its use of the cleansing fluid.

A further object is to provide a casing washer having the foregoing enumerated advantages and capacities and which is adapted to be readily and conveniently inserted into the casing or withdrawn therefrom and which is in general of simple and durable construction, reliable and efficient in operation and easy and comparatively inexpensive to manufacture.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a fragmentary view, partly in section and partly in elevation, showing a portion of the perforated casing and a casing washer embodying the present invention in use in conjunction with said casing;

Figure 2 is a view in section on line 2—2 of Figure 1;

Figure 3 is a view in longitudinal vertical section, on line 3—3 of Figure 2;

Figure 4 is a fragmentary view in horizontal section on line 4—4 of Figure 3; and

Figure 5 is a vertical sectional view on line 5—5 of Figure 4.

Referring to the drawings wherein for the sake of illustration is shown the preferred embodiment of the invention, the numeral 1 designates a section of a perforated casing such as a well casing or the

like with which the present invention is designed for use. The perforations of the casing 1 are designated at 2.

The casing washer which constitutes the present invention comprises a body portion 3 which is preferably of cylindrical form and of a diameter and length best suited to the work. The body portion 3 is formed with a chamber 4, the lower end of which is closed by a plug 5 threaded into the cylindrical body portion. The plug 5 is provided in order to permit of ready access to the interior of the lower end of the chamber 4.

The upper end of the eccentric body portion 3 has threaded connection with the lower end of the tubing 6. It will be understood that water or other suitable fluid is pumped or otherwise forced under pressure into the tube 6 or into the chamber 4 so that the tubing constitutes means for supplying fluid under pressure to the chamber 4.

The body portion 3 is formed with a number of openings, designated generally at 7, which extend from the chamber 4 through the body portion to the exterior and in each of these openings a jet, designated generally at 8, is mounted. The openings 7 and the jets 8 mounted therein are spaced angularly and longitudinally of the cylindrical body portion 3 and may be provided in any desired number. As the openings and jets are of identical construction a single description will apply to all. Each opening 7 extends radially of the cylindrical body portion and around the inner end of each opening the body portion is cut away to provide an enlarged recess 9. This recess 9 forms an annular shoulder 10. Beyond the shoulder 10 the opening 7 is internally threaded, as at 11 and is of approximately the same diameter as the recess 9. In this internally threaded portion of the opening 7 packing 12 is arranged and is held by a packing nut or follower 13 and lock washer 14. The face 15 of the shoulder 10 engaged by the packing 12 is inclined so that by tightening up the follower or nut 13 the packing will be forced into engagement with the jet 8.

Each jet 8 comprises a tubular body portion 16 preferably of cylindrical form and slidably fitted in the opening 7. The inner end of the body portion 16 of each jet 8 is open and freely communicates with the

chamber 4. The outer end of the body portion is provided with a head 17 having a discharge orifice 18 formed therein and arranged centrally thereof. The outer end 5 face or surface of the head 17 is rounded off, as at 19, from the orifices to the periphery of the body portion. A coil spring 20 encircles the inner end of the body portion 16 of each jet and engages the shoulder 10 at one end and a cotter pin 21 at its opposite end. The cotter pin 21 is fitted in diametrically opposite openings 22 provided therefor in the body portion 16 and serves as an abutment for the coil spring 15 and also as means to limit the outward movement of the jet.

When the washer is in use it is lowered into the casing 1 and fluid under pressure is pumped or forced down into the tubing 20 6 into the chamber 4. This fluid passes into the body portions 16 of the jets and acts on the inner surfaces 23 of the heads thereof to force the jets outwardly. It will be understood that the light coil springs 20 25 maintain the jets 8 inwardly of the body portion 3 except when the fluid pressure is maintained in the chamber 4. It will be noted that by virtue of the rounding off of the outer ends of the jets that the casing 1 30 is adapted to lie flush up against the discharge orifices 18 and to block these orifices and prevent escape and discharge of the fluid at all times except when the orifices are alined with the perforations 2 of the casing. This feature provides for an economical use of the cleansing fluid. Since the jets are forced outwardly by the fluid pressure they are projected tightly up against the perforations 2 and in this manner a 40 proper and effective application of the cleansing fluid is had and a washing out of obstructions or deposits in the perforations 2 is insured. When the cleansing operation has been completed pressure is no 45 longer maintained in the chamber 4 and consequently the springs 20 retract the jets into the body portion 3 of the washer.

I claim:

1. A washer for perforated casings comprising a body portion having a chamber therein and having an opening extending from the chamber to the exterior, a jet slidably mounted in said opening, means for supplying fluid under pressure to said chamber, said jet being forced outwardly by said fluid and having an orifice at its outer end and being rounded off from said orifice whereby said orifice is blocked by

the casing except when opposed to a perforation thereof.

2. A casing washer employing a washing fluid under pressure and comprising a body portion having a chamber therein and having an opening extending from the chamber to the exterior, and a jet slidably mounted in the opening and comprising a tubular body portion having its inner end open and having a head at its outer end provided with a discharge orifice, the pressure of the washing fluid on the head serving to automatically project the same.

3. A casing washer employing a washing fluid under pressure and comprising a body portion having a chamber therein and having an opening extending from the chamber to the exterior, a jet slidably mounted in the opening and designed to be projected by the direct action of the pressure of the washing fluid in the jet, and a coil spring cooperable with the jet and the casing for urging the jet inwardly of the casing.

4. A casing washer comprising a body portion having a chamber therein and having an opening extending from the chamber to the exterior, a jet slidably mounted in the opening and comprising a tubular body portion having its inner end open and having a head at its outer end provided with a discharge orifice, packing between the body portion of the washer and the body portion of the jet, and means for supplying fluid pressure to the chamber.

5. A casing washer comprising a body portion having a chamber therein and having an opening extending from the chamber to the exterior, a jet slidably mounted in the opening and comprising a tubular body portion having its inner end open and having a head at its outer end provided with a discharge orifice, a coil spring encircling the inner end of the body portion of the jet, one end of the coil spring being engaged with the body portion of the washer and a cotter pin connected with the tubular body portion of the jet and engaged with the coil spring.

6. A casing washer employing a washing fluid under pressure and comprising a body portion having a chamber therein and having an opening extending from the chamber to the exterior, and a jet slidably mounted in the opening and designed to be projected by the direct action of the washing fluid thereon.

LEWIS ELY STEPHENS.
